FUEL-PUMP.

1,161,515.

Specification of Letters Patent. Patented Nov. 23, 1915.

Application filed August 15, 1911. Serial No. 644,173.

To all whom it may concern:

Be it known that we, OSCAR P. OSTERGREN and GUSTAV FAST, subjects of the King of Sweden, residing at New York city and 5 Orange, in the counties of Kings and Essex and States of New York and New Jersey, respectively, have invented certain new and useful Improvements in Fuel-Pumps, of which the following is a full, clear, and 10 exact description, such as will enable others skilled in the art to which it appertains to make and use the same.

This invention relates to pumps, and with 15 respect to its more specific features, to fuel pumps adapted to supply oil fuel to internal combustion engines.

One of the objects of the invention is to provide an efficient device of the character referred to in which the discharge of the 20 oil shall be constant in amount.

Another object of the invention is the production of a practical pump of the character referred to which shall have substantially no clearance, thus conducing to a constant 25 discharge.

Still another object of the invention is the provision of a practical and simple pump of the character referred to in which the loss 30 of efficiency and of accurate operation due to the use of valves, such as suction valves and those of a similar character, are avoided.

Still another object of the invention is the provision of a simple device of the character described in which the time or instant of 35 the delivery stroke of the pump shall be definitely controlled, and also the provision of like means for adjusting the time of said stroke.

The invention accordingly consists in the 40 features of construction, combinations of elements and arrangement of parts which will be exemplified in the construction herein-after set forth, and the scope of the application of which will be indicated in the following claims.

Referring to the accompanying drawing, wherein is illustrated one of the possible embodiments of our invention,—Figure 1 represents a front elevation of the pump and 45 operating mechanism therefor; and Fig. 2 represents a vertical section through the pump on the line $x-x$, Fig. 1.

While viewed in some aspects the pump

herein described is capable of a variety of uses, it is more especially intended to be employed to supply oil fuel, such as crude oil, to internal combustion engines of the constant pressure type; such, for instance, as the engine illustrated and described in applicants' co-pending application, Serial No. 639,868, filed July 22, 1911, of which application this is a division.

It will facilitate the disclosure of the invention to set forth the same in its relation to internal combustion engines, and accordingly, referring now more particularly to the drawing, the numeral 1 indicates a fixed part of such an engine, in this case a cylinder, and the numeral 2 indicates the usual cam shaft driven from the crank shaft of 70 the engine through the counter-shaft 3 and the bevel gears 4 and 5 in the usual manner. Secured to the shaft 2 are eccentrics 6 and 7 disposed at substantially 180° with respect to each other and engaging eccentric straps 75 8 and 9 operating oscillatory rods 10 and 11, which latter, as will hereinafter appear, operate the pumps.

From any suitable source, oil for fuel is conducted into a reservoir or chamber 10', 80 which is of sufficient capacity to supply oil to separate pumps, one for each internal combustion engine, the reservoir 10' being thus common to the engines. Separate passageways 11' lead the oil by gravity to pump 85 chambers 12, which are continuous with the oil reservoir, except when cut off as herein-after set forth. Operating in each pump chamber is a pump plunger 13 adapted to reciprocate in said chamber and force the 90 oil out of the chambers through a check valve 14 into pipes 15 and 16, which conduct the oil to suitable valves in the cylinders of the engines. In the present embodiment the plunger 13 comprises a rod guided in the 95 walls of the reservoir, suitable packing 17 surrounding the plunger and confined by a cap 18 held in place by a spring 19. One end of the plunger 13 is extended above the top or cover 20 of the reservoir, and preferably 100 terminates in a head 21, between which and the top of the reservoir is interposed a relatively strong spring 22 adapted to raise the plunger on its inlet stroke. Preferably the plunger passes through a cap 23, closing an 105 opening in the top of the reservoir imme-

diately above the packing and cap 18, of sufficient size to permit the removal of the latter when desired.

In order that the delivery stroke of the pump may cause the discharge of a definite and constant amount of oil from the pump chamber, unaffected by any elastic conditions in the reservoir, means are provided for offering a substantially unyielding resistance to the oil on the delivery stroke, except at the discharge opening of the pump, and in the present embodiment this is effected by a valve 24, disposed in the passageway 11' and adapted to open and close said passageway. When the valve is open, oil from the reservoir gravitates into the pump chamber, and a sufficient amount of oil is supplied to the reservoir to fill the passageway and the pump chamber so that when the valve is closed the oil completely fills the pump chamber and the passageway up to and against the valve, thereby providing a pump chamber without any clearance. Under such conditions an amount of oil will be discharged from the pump chamber equal to the displacement of the piston, the device thus providing for the feed of a fixed amount of oil, dependent only upon the length of the stroke of the plunger.

The valve 24 is provided with a stem 25 passing through the oil reservoir, and out of its upper wall through an elongated guiding bearing 26, and a lever 27, loosely articulated as by being pivoted to the stem at 28, extends transversely to the stem, one arm 29 being adapted to contact with the upper face of the head 21 of the pump plunger 13, and another arm 30 terminating in the path of a lug or tooth 31 carried by the oscillatory rod 10 operated through the strap 8 surrounding one of the eccentrics 6 on the cam shaft 2. A spring 32, lighter than the spring 22 of the pump plunger, operates to depress the valve stem 25 and open the valve, the spring 32 being interposed between the inner wall of the oil reservoir and a collar 33 on the valve stem. A plug 34 is provided through which the valve 24 may be removed when required. It is to be understood that in the present embodiment two pumps are provided, each of which is similar to the one described, the description being limited to one for brevity only.

Pivoted at a suitable point, in the present instance on the oil reservoir, is a bell crank 35, one arm being connected to a governor (not shown) and the other arm having a roller 36 coöperating with the face of the oscillatory rod 10 so that it will rotate the arm about its eccentric 6 sufficiently to cause the tooth 31 to disengage the arm 30 of the lever 27 or to entirely escape said arm as the condition of running may demand. A leaf spring 37 secured to the end of the rod 10 and sliding on a smooth portion of the

frame returns the tooth 31 into the engaging line of movement, and causes the rod to follow the retrogression of the roller and remain in contact therewith. The tooth 31 has a beveled portion whereby it may freely pass the arm 30 on its return movement. In order that both of the oscillatory rods 10 and 11 may be controlled, the bell crank 35 has two arms, each provided with a roller 36 adapted to contact with the faces of the rods 10 and 11, respectively.

The operation of the mechanism will now be apparent. As the shaft 2 rotates an up and down reciprocatory motion is imparted to the rod 10. As it rises, the tooth 31 lifts the arm 30, and the spring 32 being lighter than the spring 22, the lever 27 will fulcrum on the head 21 of the pump plunger 13, and the valve 24 will be lifted and close the passageway 11'. The lever 27 will then fulcrum at its pivot 28 on the valve stem, and the arm 29 will be depressed, thus forcing the pump plunger down after the valve is closed and delivering oil from the pump chamber through the check valve 14 and into the discharge pipe leading therefrom. The pump plunger will be depressed according to the full throw of the eccentric unless the governor causes the bell crank to deflect the rod 10 and disengage the tooth 31 from the arm 30, whereupon the pumping of oil will cease and the plunger will at once return to its upper position under the influence of spring 22, the valve 24 being also immediately opened by spring 32, permitting the pump chamber to be again filled from the reservoir. The position of the arm 30 with respect to the position of the tooth 31 determines the instant of the beginning of the delivery stroke of the pump, and means are provided for adjusting and fixing said position consisting of an adjustable stop comprising a set screw 38 passing through a bracket or yoke 39 supported on the oil reservoir. The stop is adapted to contact the arm 29, and, with the position of the latter accordingly limits the position of the plunger, as will be apparent. A lock nut 40 is employed to secure the set screw in adjusted position. The stop 38 having been set as desired, the pump will begin its delivery strokes at identical points in the stroke of the operating mechanism, the amount of oil discharged being regulated by the cut-off devices operated from the governor driven by the engine, as explained.

For the sake of brevity, the description has been mainly confined to that of one pump, but it is to be understood that the pumps are identical in all respects, and that the controlling and operating devices are duplicated one for each pump, it being noted that the oscillatory rods 10 and 11 are set to operate the pumps at the desired intervals, and that the cut-off is controlled by a

single lever or bell crank pivoted on the oil reservoir and having two similar arms, one carrying one roller 36 and the other another similar roller.

- 5 It will be perceived that, prior to the delivery stroke of the reciprocating plunger or piston 13, the inlet valve 24 will be positively closed, thus confining the oil which completely fills the pump chamber and 10 avoiding any substantial clearance in the chamber, an important factor in pumps wherein the delivery is small and is desired to be constant in amount for the same length of stroke. In the present embodiment the 15 pumps operate at different times, and it is desirable that the beginning of the delivery stroke be effected at certain phases in the operation, corresponding especially to the engine phases, as will be understood, and the 20 adjusting device associated with the lever 27 and co-operating parts affords a means for accurately setting or timing the delivery stroke, while at the same time assuring that the chamber is in condition to supply oil at 25 the instant of the beginning of the delivery stroke. At the same time the cut-off devices accurately control or govern the duration of the delivery stroke, and upon cessation thereof, the inlet valve is at once forced open and 30 held open during the inlet stroke of the pump. Thus the pump described will deliver an amount of oil substantially equal to the displacement effected by the piston on its discharge stroke. It will also be noted 35 that, by the mechanism described, and assuming the parts to be operating under conditions determined by setting the stops 38, not only is the beginning of the delivery stroke maintained constant relative to the 40 phase for which the pumps have been adjusted, but variation in the duration of the delivery stroke is permitted without substantial modification of the time of beginning said stroke. Thus by the above-described 45 mechanism are accomplished, among others, the objects hereinbefore stated.

As many changes could be made in the above construction and many apparently widely different embodiments of this invention could be made without departing from the scope thereof, it is intended that all matter contained in the above description or shown in the accompanying drawing shall be interpreted as illustrative and not in a 55 limiting sense.

It is also to be understood that the language used in the following claims is intended to cover all of the generic and specific features of the invention herein described and all statements of the scope of the invention, which, as a matter of language, might be said to fall therebetween.

Having described our invention, what we claim as new and desire to secure by Letters 65 Patent is:

1. In an apparatus of the character described, in combination, a pump comprising a chamber, a piston adapted to reciprocate therein, an inlet valve, means adapted to positively cause the delivery stroke of said piston, and devices whereby the delivery stroke of the piston is effected in the pump chamber without clearance comprising means adapted to force open said inlet valve immediately upon the completion of said delivery stroke. 70 75

2. In an apparatus of the character described, in combination, a pump comprising a chamber, a piston adapted to reciprocate therein and assume a variable position at one end of its stroke, an inlet valve, and means controlled by the inlet valve for timing the delivery stroke of the piston. 80

3. In an apparatus of the character described, in combination, a plurality of pumps, a supply reservoir, open passageways connecting the pump chambers with the reservoir, means for operating the pumps at different times, and means for positively closing communication between the reservoir and a pump chamber prior to the delivery stroke from the latter pump chamber. 85 90

4. In an apparatus of the character described, in combination, a pump chamber, a piston adapted to reciprocate therein, a supply reservoir, a valve controlling communication between the chamber and reservoir, resilient means adapted to withdraw the piston from the chamber, a lighter resilient means adapted to open the valve, a lever adapted to fulcrum on the valve and having an arm adapted to effect the delivery stroke of the piston, and means to operate the lever to effect the delivery stroke. 95 100 105

5. In an apparatus of the character described, in combination, a pump chamber, a piston adapted to reciprocate therein, a supply reservoir, a valve controlling communication between the chamber and reservoir, resilient means adapted to withdraw the piston from the chamber, a lighter resilient means adapted to open the valve, a lever adapted to fulcrum on the valve and having an arm adapted to effect the delivery stroke of the piston, and a reciprocating operating device, said lever having an arm disposed in the path of the latter device. 110 115

6. In an apparatus of the character described, in combination, a pump chamber, a piston adapted to reciprocate therein, a supply reservoir, a valve controlling communication between the chamber and reservoir, a spring associated with the piston and adapted to withdraw the same from the chamber, a lighter spring adapted to open the valve, an oscillatory rod having a tooth, a lever pivoted to the valve and having arms disposed one to effect the delivery stroke of the piston and another in the path of the 120 125 130

- tooth, and means to control the instant of engagement of the arm and tooth.
7. In an apparatus of the character described, in combination, a pump chamber, a piston adapted to reciprocate therein, a supply reservoir, a valve controlling communication between the chamber and reservoir, a spring associated with the piston and adapted to withdraw the same from the chamber, a lighter spring adapted to open the valve, an oscillatory rod having a tooth, a lever pivoted to the valve and having arms disposed one to effect the delivery stroke of the piston and another in the path of the tooth, means to control the instant of engagement of the arm and tooth, and means to control the disengagement thereof.
8. In an apparatus of the character described, in combination, a pump chamber, a piston adapted to reciprocate therein, a supply reservoir, a valve controlling communication between the chamber and reservoir, a spring associated with the piston and adapted to withdraw the same from the chamber, a lighter spring adapted to open the valve, an oscillatory rod having a tooth, a lever pivoted to the valve and having arms disposed one to effect the delivery stroke of the piston and another in the path of the tooth, means to control the instant of engagement of the arm and tooth, and means to control the disengagement thereof.
9. In an apparatus of the character described, in combination, a pump chamber, a piston adapted to reciprocate therein, a supply reservoir, a valve controlling communication between the chamber and reservoir, a spring associated with the piston and adapted to withdraw the same from the chamber to a variable position, a lighter spring adapted to open the valve, an oscillatory rod having a tooth, a lever pivoted to the valve and having arms disposed one to effect the delivery stroke of the piston and another in the path of the tooth, and means to control the instant of engagement of the arm and tooth.
10. In an apparatus of the character described, in combination, a reservoir, a plurality of pump chambers having passageways communicating with the reservoir, a piston adapted to reciprocate in each chamber, valves controlling the passageways, resilient means for causing the inlet stroke of each piston, resilient means for opening each valve, and means for operating the pistons at different times comprising devices connected to the valves and adapted to close the valves prior to the delivery stroke of the pistons, respectively.
11. In an apparatus of the character described, in combination, a plurality of pumps comprising chambers and pistons adapted to reciprocate therein, a common supply reservoir for said pumps, valves controlling communication between the reservoir and the pumps, resilient means for causing the inlet stroke of each piston, resilient means for opening each valve, means for operating the pistons at different times comprising devices connected to the valves and adapted to close the valves prior to the delivery stroke of the pistons, respectively, and means to vary the duration of the delivery stroke of the respective pumps.
12. In an apparatus of the character described, in combination, a pump comprising a chamber, a piston adapted to reciprocate therein, an inlet valve, a lever loosely articulated with said valve and disposed in the path of the piston, and means to oscillate said lever.
13. In an apparatus of the character described, in combination, a pump comprising a chamber, a piston adapted to reciprocate therein, an inlet valve, a lever loosely articulated with said valve and disposed in the path of the piston, means to oscillate said lever, and means adapted to limit the oscillation of the lever in one direction.
14. In an apparatus of the character described, in combination, a pump comprising a chamber, a piston adapted to reciprocate therein, an inlet valve, a lever loosely articulated with said valve and disposed in the path of the piston, means to oscillate said lever, and an adjustable stop device disposed in the path of said lever.
